(57) **CLAIM**

The ornamental design of a portion of cushion for respiratory mask, as shown and described.

DESCRIPTION

FIG. 1 is a front perspective view of a portion of cushion for respiratory mask showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Where included, broken lines showing environment or structure are for illustrative purposes only and form no part of the claimed design. FIGS. 1–8 use stippling to indicate surface shading.
